APPARATUS FOR PERFORATING SHEET MATERIAL

Marley E. Bechtel, Kenmore, N. Y., assignor to Irene N. Bechtel, Kenmore, N. Y.

Application February 13, 1942, Serial No. 430,774

7 Claims. (CL. 164—90)

This invention relates more particularly to an apparatus for perforating sheet metal although the same may be advantageously employed for operating on other like material.

One of the objects of this invention is to provide perforating units for apparatus of this character which permit varying numbers of these units to be employed in a perforating apparatus depending on the number of holes which are desired.

Another object is to so construct the unit that the same can be quickly installed in various locations in the apparatus for use and also quickly removed therefrom when no longer required and thus facilitate the work.

A further object of the invention is to provide simple and efficient means for accurately alining the punch and die of a perforating unit preparatory to forming a hole in the workpiece.

A still further object is to so mount the punch of the punch section of each unit that the same can be quickly inserted in its holder and also removed therefrom for replacing a broken punch or other purpose.

In the accompanying drawings:

Fig. 1 is a front elevation of a sheet material perforating apparatus embodying one form of this invention.

Fig. 2 is a side elevation of the same.

Fig. 3 is a top plan view, taken on line 2—2, Fig. 1, looking downwardly, showing the lower part of the perforating apparatus.

Figs. 4 and 5 are vertical sections, on an enlarged scale, taken on lines 4—4 and 5—5, Fig. 3, respectively.

Fig. 6 is a vertical section of the casing and stripper springs of one of the punch sections of the perforating apparatus showing the first step in the method of assembling the same.

Fig. 7 is an end view of the same.

Fig. 8 is a view similar to Fig. 6 showing the second step in the method of assembling the casing and stripper spring of a punch section.

Fig. 9 is a cross section taken on line 9—9, Fig. 8.

Fig. 10 is a view similar to Figs. 6 and 8 showing the third step in the method of assembling the casing and stripper spring of a punch section.

Fig. 11 is a cross section taken on line 11—11, Fig. 10.

Fig. 12 is a view similar to Figs. 6, 8 and 10 showing the last step in the method of assembling the casing, stripper spring and punch of a punch section.

Fig. 13 is an end view of the same.

Fig. 14 is side elevation of a modified form of this invention.

Fig. 15 is a plan view of the same taken on line 15—15, Fig. 14 looking downwardly.

Figs. 16 and 17 are fragmentary vertical sections, on an enlarged scale, taken respectively on the correspondingly numbered lines in Fig. 14.

In the following description similar reference characters indicate corresponding parts in the several figures of the drawings.

This perforating apparatus is adapted to be used in connection with a power press which may be of any suitable or approved construction, 15 those parts of the same shown in the drawings consisting of a lower stationary table, bed or plate 20 and an upper reciprocating ram 21 which moves vertically toward and from the bed.

In general this perforating apparatus includes 20 one or more perforating units each of which comprises a punching section and a die section which cooperate for producing a hole in a work sheet 22 and which are mounted on the members of a press one of which is movable relative

25 to the other, the punching section in the present case being mounted on the stationary bed 20 and the die section on the movable ram 21. In practice a plurality of punching sections are mounted selectively on a horizontal lower supporting plate 23 which is provided over the central part of its area with a plurality of punch section receiving openings 24 and a plurality of die sections are mounted selectively on a horizontal upper supporting plate 25 which is pro-

30 vided over the central part of its area with a plurality of die section receiving openings which are arranged respectively in line with the corresponding punch receiving openings in the lower supporting plate.

35 40 Each of the punching sections is constructed as follows:

The numeral 26 represents a punch guide tube provided on the central part of its periphery with a cylindrical neck 27 which fits snugly in

45 one of the openings 24 of the lower supporting plate 23, while the lower end of this tube projects below the underside of this plate and is provided with an external screw thread and the upper end of this tube is provided with an external flange 28 bearing against the upper side of this plate, as shown in Fig. 5.

The numeral 29 represents a punch casing which preferably has the form of an upright cylinder and provided at its upper end with an internal screw thread 30 which works on

the external thread of the companion guide tube so that upon tightening this casing on the tube the upper end of this casing will be pressed against the underside of this supporting plate. By these means this tube and casing may be quickly and firmly secured to this supporting part for retaining the same and the parts carried thereby in the proper position for accurately cooperating with a companion die section and these means also permit of readily detaching the punch unit from the lower supporting plate when the same is not required or when the punch mounted thereon must be sharpened or replaced when broken.

Arranged axially within the punch guide tube and the casing is a punch, the body 31 of which projects downwardly below the lower end of the casing and the bit or cutter 32 at the upper end of which slides in the bore of the guide tube 26 and is adapted to be arranged in an inoperative position within this tube or in an operative position in which it projects above the guide tube. The casing 29 is retracted and yieldingly held in its retracted position by a stripper spring 33 preferably of helical form which is arranged within the casing around the punch and bears at its upper end against a downwardly facing upper shoulder 34 at the upper end of the casing, while the lower end of this spring bears against an upwardly facing lower shoulder on the lower part of the punch. This lower shoulder is formed on the punch by making a part of the punch adjacent to its lower or rear end of oblong form in cross section and thus producing two lugs 35 which provide upper and lower shoulders on the opposite sides of the punch. The downward or retracting movement of the punch under the pressure of the stripper spring 33 is limited by stop means which preferably consist of a shoulder formed by two stops 36 arranged on opposite sides of the casing and adapted to be engaged on their upper sides by the stop lugs 35 of the punch. Each of these stops 36 is preferably formed by cutting a circumferential slit 37 in the lower part of the casing and bending inwardly that part of the casing between the respective slit and the lower end of the casing so that the same projects inwardly from the bore of the casing and into the path of one of the stop lugs 35 on the punch. The procedure which is followed in preparing the casing and assembling the stripper spring and punch therewith is as follows:

The first step in the preparation of the casing is to provide the same on the diametrically opposite sides of its lower part with two circumferential slits 33 and then inserting the stripper spring into the casing so that the upper end of the same engages the upper shoulder 34 of the casing, as shown in Figs. 6 and 7. The second step in the method of assembling the spring and casing is now performed by inserting into the casing from its bottom a mandrel having an upper end 38 of small diameter which enters the lower part of the spring, an oblong intermediate part forming a pair of lugs 39 projecting from diametrically opposite sides of the central part of this mandrel and engaging with the lower end of the spring, and a lower end 40 of large diameter forming an upwardly facing shoulder 41 adapted to engage the lower end of the casing, as shown in Figs. 8 and 9. Upon inserting the mandrel into the casing and spring the latter is compressed by engagement of the lugs 39 with the lower end of this spring and the upward movement of the mandrel into the casing is lim-

ited by engagement of the shoulder 41 of the mandrel with the lower end of the casing.

While the mandrel is thus inserted in the casing and the stripper spring is compressed, the third step in the method of assembling the casing and stripper spring is performed by bending inwardly those portions of the casing between its slits 37 and the lower end of the casing against opposite sides of the narrow part of the oblong section of the mandrel, as shown in Figs. 10 and 11, so as to make the adjacent part of the casing oblong in cross section and form the stops 36 which project underneath the lower end of the stripper spring and prevent the latter from escaping from the casing upon withdrawing the mandrel from the casing.

Completion of the assemblage of the punch with the casing and stripper spring is effected by placing the punch in alignment with the axis of the casing and stripper spring and so that the oblong part of the punch registers with the oblong part of the casing. After the punch is arranged in this position the same is moved into the casing and stripper spring until the stop lugs 35 of the punch are above the stops 36 on the casing after which the punch is turned one-quarter circle about its axis, whereby the stop lugs 35 of the punch are carried over the stops 36 of the casing. Upon now releasing the upward pressure against the punch the stop lugs 35 of the latter will bear against the upper sides of the casing stops 36 and hold the stripper spring in its compressed position, as shown in Figs. 12 and 13.

Whenever it is desired to remove the punch from the casing and stripper spring for the purpose of sharpening its bit or, when broken, to replace the same by a new punch, this can be effected very quickly and easily by first turning the punch until its oblong part formed by the stop lugs 35 is in register with the oblong lower part of the bore of the casing between the stops 36 of the latter after which the punch can be freely withdrawn from the casing.

When assembling the elements of a punching section on the lower supporting plate of the perforating mechanism, the guide tube of this section is first placed with its neck in the desired locating opening 24 of the lower supporting plate so that the flange of this tube engages with the top of this plate and then the bit of the punch is introduced into the bore or opening of this tube from the lower end of the latter and then the upper end of the casing is screwed onto the lower end of the guide tube 26 and engaged firmly with the underside of the lower supporting plate.

The punches of the several punch units engage their lower ends with the upper side of the bed 20 of the press and the supporting plate 23 is mounted on this bed so as to be capable of moving vertically thereto for the purpose of lowering the casings 29 and guide tubes 26 so as to expose the top end of the punches above the guide tubes 26 for cooperation with the dies to produce holes in the workpiece and to withdraw the workpiece from said punches after the holes have been formed in the same. The means for thus mounting the lower supporting plate on the press bed are constructed as follows:

The numerals 42, 42 represent supporting bars secured crosswise by screws 43 to the underside of the front and rear edge portions of the lower supporting plate 23 and guided relative to the press bed by means of posts 44 which are connected at their lower ends by screw joints 45

with the press bed and provided on their upper parts with cylindrical bodies which pass through correspondingly shaped openings in the ends of the supporting bar 42 for guiding the latter in its vertical movements. The lower supporting plate 23, cross bars 42 and the parts mounted thereon are yieldingly held in an elevated position relative to the press bed by means of lifting springs 46 interposed between the underside of the supporting bars and the upper side of the lower bolsters 47 which are secured to the top of the press bed. The upward movement of the supporting bars 42 under the pressure of the lifting springs 46 is limited by stops 48 formed on the upper ends of the guide posts 44, and the upper and lower ends of these springs are seated in recesses 49, 50 formed in the underside of the cross bars 42 and the upper side of the bolsters 47 for holding these springs against lateral displacement. The lower bolsters are preferably secured to the press bed by means of the guide posts 44 which latter pass through the bolsters and are provided with shoulders 51 bearing against the top of the lower bolsters, as shown in Fig. 4.

On its upper side the lower supporting plate may be provided with suitable gages 52 against which an edge of the workpiece may be placed for properly locating the same relative to the punch and die sections to produce the holes in the workpiece in the desired places.

Each of the die sections which cooperates with one of the punch sections for producing a hole in the workpiece is constructed as follows:

The numeral 53 represents the tubular body of a die, the central part of which has a cylindrical periphery 54 fitting closely or snugly into one of the die openings in the upper supporting plate 25 while the lower end of the same has a cutting edge around its bore and an external flange 55 which bears against the underside of said plate, and the upper end of this die body is provided with an external screw thread 56, as shown in Fig. 5.

Above the upper supporting plate 25 are arranged a plurality of tubular clamping sleeves or nuts 57. Each of these clamping sleeves has its lower end bearing against the top of the upper supporting plate 25 and provided with an internal screw thread 58 which receives the external thread 56 of the respective die body and cooperates with the same for detachably securing the respective die section to the upper supporting plate, as shown in Fig. 5.

The upper ends of the several die clamping sleeves engage with the underside of an upper pressing plate 59 which is secured to the underside of the ram by screws 60, as shown in Fig. 1.

The upper supporting plate 25 is secured to this pressing plate in a spaced relation thereto by means of spacing sleeves 61 interposed between the marginal parts of the upper supporting plate and the pressing plate and fastening screws 62 passing through this plate and the respective spacing sleeves and secured with their upper threaded ends to the pressing plate and bearing with the heads at their lower ends against the underside of the upper supporting plate, as shown in Fig. 4.

At its upper end each of the clamping sleeves 57 is provided with a discharge opening 63 which extends from its bore to its periphery and through which escape, to the exterior of the apparatus, the slugs which are formed by the stock which

is removed from the workpiece during the formation of the holes therein.

The operation of this apparatus is as follows:

When the ram is raised the lower supporting plate is raised by the stripper spring 33 and the bars 42 are raised by the lifting springs 46 so that the upper ends of the punches are below the top of the guide tubes 26 and a gap is formed between the lower punch sections and the upper die sections of the several perforating units, as shown in Figs. 1, 2, 4 and 5. While the parts are in this position the work sheet 22 is placed upon the guide tubes of the several punch sections, as shown by broken lines in Fig. 5, and then the ram is lowered. During the first part of the downward movement of the ram the lower supporting plate 23 and the parts connected therewith remain at rest until the lower ends of the several die bodies of the die sections bear against the top of the workpiece and clamp the same against the upper ends of the guide tubes of the several punch sections and hold this workpiece securely against lateral displacement. During the continued downward movement of the ram the workpiece, together with the punch guide tubes, punch casings and lower supporting plate 23, are depressed while the punches are at rest thereby causing the upper end of each punch to pass through the adjacent part of the workpiece and in the bore of the die, thereby punching a slug out of the workpiece and into the die and forming a hole in the workpiece. The slugs which are successively removed from the workpiece are pushed upwardly into the dies and eventually escape to the exterior of the apparatus through the openings 63 at the upper ends of the clamping sleeves 57. During the descent of the punch casings 29 the springs 33 are further compressed and when the ram rises and the grip of the dies on the workpiece is released, the stripper springs hold the punches down in engagement with the press bed 20 whereby the upper or bit ends of the punches are withdrawn from the workpiece and the latter is free to be removed from the punching apparatus and replaced by another unpunched workpiece.

By mounting the punch sections on the stationary lower supporting plate the apparatus can be operated faster and with less power inasmuch as the punch sections are lighter than the die sections. Moreover the punch sections contain more parts and can be more easily mounted and operated on the press bed than on the ram. It is to be understood, however, that this invention permits of mounting the punch sections on the ram and the die sections on the press bed inasmuch as such reversal is possible without any material change in construction of the several parts of this mechanism.

By forming a plurality of holes 24 in the punch supporting plate and a plurality of corresponding holes 18 in the die supporting plate, it is possible to select the corresponding pairs of such openings in these plates for locating the perforating units in various places to suit the requirements of the particular job in hand.

The construction of this invention as shown in Figs. 1-13 is more particularly adapted for direct connection with the bed and ram of a power press. For the purpose of enabling this invention to be used in connection with a power press without any fixed connection of the same the punching apparatus may be mounted as follows:

Referring to Figs. 14-17, the numerals 64 and 65 represent lower and upper supporting plates

which are arranged one above the other and upon which the punch sections and the die sections of the punching units are respectively mounted in the same manner so that the lower ends 31 of the punches engage with the top of the press bed 20 and the upper ends of the die clamping sleeves 57 engage with the underside of the pressing plate 59.

In this construction the lower ends of the punches merely rest on the press bed and the rear ends of the supporting plates are connected with each other so that the upper supporting plate can be tilted upwardly for producing a gap between the lower and upper supporting plates for the introduction and removal of the work-pieces into and out of their perforating position between the punch sections and die sections of the several perforating units.

For this purpose the rear ends of the supporting plates are pivotally connected by means which preferably comprise a plurality of hinges the number of which are varied according to the width of the lower and upper supporting plates 64, 65, two hinges being employed in Fig. 15 as an example. Each of these hinges includes a horizontal pintle 66 mounted on an upper hinge leaf 661 secured to the upper supporting plate 65 and a lower hinge leaf 671 mounted on the lower supporting plate 64 and provided with a vertically elongated eye 67 which loosely receives the pintle of the companion leaf, as shown in Figs. 14 and 15. When the ram is raised the upper supporting plate is raised to form a gap between the same and the lower supporting plate, which raising of the upper plate may be effected either manually or by connecting the front edge of the upper supporting plate by a chain 68, or the like, with the front part of the ram, so that the upper supporting plate will rise and fall in unison with the ram.

When using the apparatus shown in Figs. 14-17 the lower ends of the several punches rest freely on top of the press bed 20 and the springs of the several punch sections hold the lower supporting plate 64 in an elevated position so that the upper ends of the punch guide tubes 26 are a little above the upper ends of the punches, as shown in the lower part of Fig. 17. After the operator places a workpiece on the punch guide tubes the upper supporting plate is lowered so that the lower ends of the dies of the several die sections engage with the upper side of the workpiece, as shown in Fig. 17. During the last part of the descent of the ram the presser plate 59 bears downwardly on the upper ends of the several die clamping sleeves 57 and depresses the same together with the punch guide tubes, whereby the upper ends of the punches pass through a plurality of places on the workpiece and push the slugs resulting from such perforation upwardly into the several die clamping sleeves. During the initial part of the subsequent upward movement of the upper supporting plate 65, the lower supporting plate is raised in unison therewith by the stripper springs 33 until the latter have reached the limit of their expansion permitted by the casings 28 at which time the upper ends of the guide tubes 26 are a little above the bits of the punches and the workpiece has been stripped from the same. Thereafter the upper supporting plate 65 and the die sections are moved upwardly independently of the punch sections leaving the space between the die sections and punch sections clear for removing the finished work and replacing the same by new work.

In order to accurately align the die sections with the punch sections before the punches enter the openings of the dies, alining means are provided which are preferably constructed as follows and shown in Figs. 14, 15 and 16:

The numeral 69 represents alining or guide tubes arranged adjacent to the side edges of the lower supporting plate 64 and each projecting downward through an opening in the adjacent part of the lower supporting plate 64 and provided at its lower end with an external screw thread and provided at its upper end with an external flange 70 which bears against the upper side of the lower supporting plate. This alining tube is secured to the lower supporting plate by an internally screw threaded coupling sleeve 71 which is connected with the lower end of the respective alining tube and bears against the underside of the lower supporting plate.

Below each alining tube 69 is arranged a tubular guide casing 72 which is provided at its lower end with an internal upwardly facing shoulder 73 and has its upper end connected with the internally threaded coupling sleeve 71. The numeral 74 represents an upright supporting pin which is guided in the lower end of the guide casing 72 and has its upper part arranged within this casing while its lower end rests on the bed 20 of the press. The guide tube 69 and parts connected therewith is yieldingly held in an elevated position by a lifting or stripper spring 75 arranged within the guide casing 72 and around the upper part of the supporting pin and bearing at its upper end against the lower end of the guide tube 69 and at its lower end against a lower shoulder 76 of the guide casing. Upward movement of the guide casing and the parts connected therewith is limited relative to the supporting pin 74 by a shoulder 77 on the guide casing engaging with the shoulder 73 on the supporting pin.

The numeral 78 represents upper guide tubes arranged on the upper supporting plate 65 above the lower guide tubes 69 and each passing upwardly through an opening in this plate and provided with an external flange 79 bearing against the underside of the upper supporting plate. The upper guide tube is secured to the upper supporting plate by an internally screw threaded clamping sleeve 80 connected with the upper end of the upper guide tube 78 and bearing with its lower end against the upper side of the upper supporting plate, as shown in Fig. 16. Above, the upper guide tube 78 is arranged an upper guide casing 81 which is connected at its lower end with the coupling sleeve 80 and provided at its upper end with an internal downwardly facing shoulder 82. The numeral 83 represents an upright alining pin which has its upper part guided in the upper end of the upper guide casing 81 and its lower part guided in the lower end of the upper guide tube. The upper end of the alining pin is adapted to be engaged by the underside of the presser plate 59 and the lower end of the same is adapted to engage with the bore 84 of the respective alining tube 69. The entrance of the alining pin 83 into alining opening 84 is facilitated by providing this pin with a conical lower end 85 and providing the alining tube 69 with a conical upper end 86 which conical ends are adapted to cooperate for telescoping this pin and alining tube preparatory to engaging the punches and dies for producing holes in the workpiece.

Each of the alining pins is yieldingly held in its raised position relative to the upper support-

ing plate and die sections by a cushion spring 87 arranged within the guide tube 18 and casing 81 and around the respective alining pin and bearing at its upper end against a downwardly facing shoulder 88 on the alining pin and at its lower end against an upwardly facing shoulder 89 on the lower part of the guide tube 18. Upward movement of the alining pin relative to the upper supporting plate under the pressure of the cushion spring 83 is limited by an upwardly facing shoulder 90 on this pin engaging with the shoulder 83 on the guide casing 81.

The hinge connection between the rear ends of the supporting plate is such that there is sufficient play between the hinge pintle and hinge eyes that the upper supporting plate can swing freely in an arc toward and from the lower supporting plate but still permit each of the dies to accurately aline its die opening with the axis of the companion punch so they can move properly relative to one another for producing a hole in the workpiece.

If during the descent of the upper supporting plate the dies thereon are not in exact register with the corresponding punches on the lower supporting plate the lower conical ends of the alining pins will engage the upper conical ends of the respective alining tubes and thus produce a wedge or cam action by cooperation of these conical ends whereby the alining pins will be deflected until they are axially in line with the alining tubes and are then permitted to pass downward into said tubes.

Fig. 16 indicates the position of one of the alining pins just after the same has entered the opening in the companion alining tube and has shifted the upper supporting plate so that dies thereon are in axial alinement with the corresponding punches, preparatory to producing a perforating operation, as shown in Fig. 17. Upon now continuing the downward movement of the upper supporting plate the several dies thereon will press the workpiece downwardly on the corresponding punches and perforate the workpiece accordingly. By employing the cushion springs 87 it is possible for the alining pins to yield somewhat when their conical ends engage the conical ends of the alining tubes and thus permit the alining or centering of the same to be effected easily and noiselessly.

If desired the lifting of the upper supporting plate relative to the lower supporting plate may be effected by spring means, such as the helical springs 91, interposed between the front parts of these plates adjacent to the front corners thereof, as shown in Fig. 14.

The upper side of the lower supporting plate 64 may also be provided with gages 92 against which the workpiece to be perforated may be placed for locating the same preparatory to the punching operation.

Owing to the simplicity of these perforating units, the same can be manufactured at low cost. The same are of sturdy construction and not liable to get out of order. Moreover, the sections of the several units can be quickly applied to and removed from the supporting plates thus rendering this apparatus particularly suitable for readily changing from one punching set-up to another.

If desired the supporting plates may be strengthened by providing the same with ribs or flanges such, for example, as the downwardly projecting flange 641 arranged at the front edge

of the lower supporting plate 64, as shown in Fig. 14.

I claim as my invention:

1. A perforating apparatus comprising a supporting plate provided with an opening, a guide tube arranged in said opening and provided at one end with a flange engaging one side of said plate, a casing connected by a screw joint with the other end of said guide tube and bearing against the opposite side of said plate and provided with front and rear shoulders, a punch having a bit at its front end sliding in said guide tube and having its body arranged in said casing and provided with a shoulder engaging with the rear shoulder on the casing and having its rear end projecting beyond the casing, a spring arranged in the casing and bearing at one end against the front shoulder of the casing and bearing at its opposite end against a shoulder on said punch, and a die cooperating with said punch.

2. A perforating apparatus comprising a supporting plate provided with an opening, a guide tube arranged in said opening and provided at one end with a flange engaging one side of said plate, a casing connected by a screw joint with the other end of said guide tube and bearing against the opposite side of said plate and provided with front and rear shoulders, a punch having a bit at its front end sliding in said guide tube and having its body arranged in said casing and provided with a shoulder engaging with the rear shoulder on the casing and having its rear end projecting beyond the casing, a spring arranged in the casing and bearing at one end against the front shoulder of the casing and bearing at its opposite end against shoulders on said punch, and a die cooperating with said punch, said shoulders on the punch being produced thereon by making a part of its body transversely of oblong form, and said rear shoulder on the casing being formed thereon by circumferentially slitting said casing on diametrically opposite sides of its lower part and bending inwardly those parts of the casing between said slits and the rear end of said casing so that the respective part of said casing is of oblong form and permits the passage of the oblong part of the punch therethrough.

3. A perforating apparatus comprising two supporting plates which are pivotally connected at one pair of their corresponding edges and which are adapted to be placed between two relatively movable members of a press, a punch mounted on one of said supporting plates and engaging one of said press members, a die secured to the other supporting plate by means which engage the other press member, and means for alining said punch and die preparatory to the cooperation between the same for producing a hole in a workpiece, including an alining pin yieldingly mounted on one of said plates and engaging one of said members, an alining tube mounted on the other plate and cooperating with said pin, and means for yieldingly supporting and guiding the other supporting plate on the respective press member including a casing connected with said alining tube, a guide post which engages the last mentioned press member and upon which said casing slides, and spring means interposed between said alining tube and guide post and holding said alining tube away from the last mentioned press member.

4. A perforating apparatus comprising two supporting plates which are pivotally connected

at one pair of their corresponding edges and which are adapted to be placed between two relatively movable members of a press, a punch mounted on one of said supporting plates and engaging one of said press members, a die secured to the other supporting plate by means which engage the other press member, and means for alining said punch and die preparatory to the cooperation between the same for producing a hole in a workpiece, including an alining pin 10 yieldingly mounted on one of said plates and engaging one of said members, an alining tube mounted on the other plate and cooperating with said pin, and means for yieldingly supporting and guiding the other supporting plate on the respective press member including a casing connected with said alining tube, a guide post which engages the last mentioned press member and upon which said casing slides, and spring means interposed between said alining tube and guide post and holding said alining tube away from the last mentioned press member, said alining pin and alining tube having opposed conical ends which are adapted to cooperate and cause the same to be centered relative to one another.

5. A perforating apparatus comprising two supporting plates which are pivotally connected at one pair of the corresponding edges and which are adapted to be placed between two relatively movable members of a press, a punch mounted on one of said supporting plates and engaging one of said press members, a die secured to the other supporting plate by means which engage the other press member, and means for alining said punch and die preparatory to the cooperation between the same for producing a hole in a workpiece, including an alining pin engaging one of said press members, a guide post engaging the other press member, a tubular guide for said alining pin, a supporting plate which carries said tubular guide, spring means for projecting said alining pin arranged between the same and guide

10 tube, a casing in which said guide post slides, an alining tube which receives said alining pin and which is connected with said casing, another supporting plate which carries said alining tube and casing, and a spring interposed between said alining tube and guide post and which operates to move the plate which carries the alining tube away from the press member which is engaged by said guide post.

15 6. A perforating apparatus comprising a supporting plate provided with an opening, a guide tube mounted in said opening, a casing connected at its front end with said guide tube and provided at its rear end with an internal shoulder, a punch arranged in said casing and having its front end guided in said tube and its rear end projecting beyond the rear end of said casing and provided on its side with a rearwardly facing shoulder adapted to engage with the shoulder 20 of said casing and the punch being also provided with a forwardly facing shoulder, and a spring arranged in said casing and bearing against the forwardly facing shoulder of the punch.

25 7. A perforating apparatus comprising a supporting plate provided with an opening, a guide tube mounted in said opening, a casing connected at its front end with said guide tube and provided at its rear with an internal shoulder, a punch arranged in said casing and having its 30 front end guided in said tube and its rear end projecting beyond the rear end of said casing and provided on its side with a rearwardly facing shoulder adapted to engage with the shoulder of said casing and the punch being also provided with a forwardly facing shoulder, and a spring 35 arranged in said casing and bearing against the forwardly facing shoulder of the punch, said shoulder on the casing being formed by a part bent inwardly from said casing below a slit 40 therein.
